UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

INTERNAL-COMBUSTION ENGINE.

Original application filed September 1, 1920, Serial No. 407,443. Divided and this application filed February 6, 1925. Serial No. 7,266.

To all whom it may concern:

Be it known that I, LIONEL M. WOOLSON, a citizen of the United States, and resident of Detroit, Wayne County, State of Michigan, have invented certain new and useful Improvements in Internal-Combustion Engines, of which the following is a specification.

This invention relates to internal combustion engines, particularly to the fuel feeding mechanism thereof, and is a division of application Serial No. 407,443, filed September 1, 1920.

One of the objects of the invention is to provide means for utilizing the heavier grades of fuel in an internal combustion engine, while at the same time facilitating the starting of such engines.

Another object of the invention is to provide means for supplying an internal combustion engine with both a light and a heavy fuel from a single source of supply.

Another object of the invention is to provide means for utilizing some of the heat of a combustion heater to distill a fractional part of the heavier fuel for use in starting, as well as for operating the combustion heater in connection with the engine.

Other objects of the invention will appear from the following description taken in connection with the drawing which forms a part of this specification, and in which the single figure is a side elevation of an internal combustion engine embodying the invention, parts being broken away for better illustration, and equipped with a combustion heater and still.

With the heavy fuels, such as kerosene, that it is now desired to use in internal combustion engines, difficulties in starting are encountered and where a combustion heater is used on the engine it is difficult to make it operate satisfactorily on these heavier grades of fuel. To obviate the necessity of having two definite sources of fuel supply, one a heavy fuel for running the engine after it is warmed up, and the other a lighter fuel for starting and for feeding the combustion heater, this invention contemplates a single source of fuel supply and the use of a still in connection with the engine for separating some of the lighter fractions from the heavy fuel and feeding these lighter distilled fractions to

the engine carburetor for starting, and to 55 the combustion heater continuously.

Referring to the drawing, which is illustrative of the invention, 10 represents an internal combustion engine having an intake conduit 11, a carburetor 12 connected thereto, and an exhaust pipe 13, of somewhat usual form. The carburetor 12 receives its liquid fuel from either of two float chambers 14 and 15, and a switch valve 16 may be operated to determine which of the float 60 chambers shall supply the carburetor.

A source of fuel supply is shown in the form of a tank 17 which may be mounted high enough to permit the withdrawal of fuel therefrom by gravity, or it may be 65 mounted in a lower position, as shown, and have connected to it, as by a pipe 18, a small pump 19 which is operated by the engine and adapted to supply pressure to the tank 17. The tank 17 may be connected to one 70 of the float chambers, as 15, by a pipe 20 through a still which will be hereinafter described.

A combustion heater 22 is adapted to heat the mixture passing from the carburetor 12 75 to the engine through the intake conduit 11. This heater, of itself, is of well known form and comprises a combustion chamber 23, having an outlet 24 into the intake conduit, a spark plug 25 for igniting the mixture in the chamber, and a pipe 26 for supplying mixture to the chamber 23 as from a small carburetor 27 which is shown connected to the float chamber 14 of the carburetor 12. A small glass window 28 permits the operation of the combustion heater to be observed and the admission of additional air thereto may be controlled by a small valve 29 for the purpose of obtaining the best mixture.

It will be understood that the combustion heater operates by the suction of the engine since the conduit 24 enters the intake conduit above the throttle valve. The engine suction draws a combustible mixture 80 from the carburetor 27 through the pipe 26 and into the chamber 23 where it is fired by the spark plug 25. The hot burnt mixture passes through the opening 24 into the intake conduit and thereby heats the mixture 85 passing to the engine.

In the form of the invention shown, a still 90 is mounted on the combustion chamber

23. The still is in the form of an enclosed chamber surrounding the combustion chamber and is connected to the fuel supply 17 by the pipe 20 hereinabove described. A pipe 32 also connects the lower part of the still with the float chamber 15.

By the pressure in the tank 17, supplied by the pump 19, above referred to, the heavy fuel is fed to the still 30, and a valve 33 therein, controlled by a float 34, determines the level to which the liquid is permitted to rise in the still. The heat for the still is supplied by the combustion chamber 23 and fins 35 may be provided to assist radiation 15 at this point.

A condenser for the still is shown in the form of a tank 36 which may be supplied with radiation fins 37, and this tank, in addition to performing the function of a condenser, is also in the nature of an auxiliary supply tank for the lighter fractions of fuel that are received by it from the still 30. A pipe 38 connects the upper part of the still 30 with the tank 36 so that the vapors produced by the still will pass to the condenser where they will be condensed and stored.

The condenser 36 is connected to the float chamber 14 of the carburetor 12 as by a pipe 39, and thus the condenser or supply tank 36 will supply the carburetor 12 with fuel when the switch valve 16 connects the float 14 to the carburetor, and regardless of the position of the switch valve 16, the condenser 36 will supply the carburetor 27 with fuel for the combustion heater 22. Thus it is possible to start the engine on the lighter fuel contained in the condenser 36 and so operate it until the engine is 40 warm enough to run on kerosene or other heavier fuel. But even after the switch valve 16 has been so turned that the engine will run on the heavier fuel supplied from the float chamber 15, the combustion heater 45 22 will operate on the lighter fuel supplied to the float chamber 14 by the condenser 36. Of course the still 30 will continue to operate and will replenish the supply of fuel in the condenser 36 as fast as, or faster than 50 it is withdrawn therefrom by the combustion heater, so that there will always be sufficient lighter fuel in the condenser 36 to start the engine after it has been stopped for a period of time.

55. In the form of the invention illustrated, it is probable that a considerable amount of mixture would be fed to the combustion

heater due to the fact that much of its heat would be absorbed by the still, but, within reasonable limits, any desired amount of mixture can be fed to the combustion heater so that there will be sufficient heat both for operating the still and for heating the mixture passing from the carburetor 12 to the engine. 65

It will be understood that the forms shown herein are illustrative only of the invention, and various modifications thereof may be made without departing from the spirit or scope of the invention as defined by the claims. 70

What is claimed is:

1. In an internal combustion engine, the combination with a combustion heater for heating the mixture passing to the engine, 75 of a still operated by the heat from said combustion heater and adapted to supply fuel for the engine.

2. In an internal combustion engine, the combination with the engine intake conduit, 80 and a combustion heater connected thereto, of a still operated by the heat from said combustion heater and adapted to supply fuel for the engine.

3. In an internal combustion engine, the 85 combination with a combustion heater operated by engine suction, of a still operated by heat from said combustion heater, and a cooler connected to the still and to the engine. 90

4. In an internal combustion engine, the combination with the engine carburetor and a combustion heater having a separate carburetor, of a still operated by heat from the combustion heater, and a condenser for the 95 still connected to both said carburetors and to the combustion heater.

5. In an internal combustion engine, the combination with the engine carburetor and a combustion heater, of a still operated by 100 heat from the combustion heater, and a condenser for the still adapted to supply to the carburetor fuel for starting the engine only, and all the fuel for the combustion heater.

6. In an internal combustion engine, the 105 combination of an engine cylinder, a still, and a combustion heater operated by the engine and adapted to heat said still.

7. In an internal combustion engine, the combination of an engine and a combustion 110 heater, of an oil still operated by the engine and heated by the combustion heater.

In testimony whereof I affix my signature.
LIONEL M. WOOLSON.
